UNITED STATES PATENT OFFICE.

CHARLES A. BICKFORD, OF CHICAGO, ILLINOIS.

DESIGN FOR A RING.

50,293.

Specification for Design.

Patented Feb. 13, 1917.

Application filed October 11, 1916. Serial No. 125,124. Term of patent 3½ years.

To all whom it may concern:

Be it known that I, CHARLES A. BICKFORD, a citizen of the United States, residing at Chicago, in the county of Cook and State of Illinois, have invented a new, original, and ornamental Design for a Ring, of which the following is a specification, reference being made to the accompanying drawing, forming a part thereof.

The drawing shows two views of the ring showing my new design.

Copies of this patent may be obtained for five cents each, by addressing the "Commissioner of Patents, Washington, D. C."

Figure 1 of the drawing is a horizontal view of my design showing particularly the gem and its immediate setting; Fig. 2 of the drawing is a vertical view of my design showing a more complete view of the design in connection with the ring proper.

I claim:

The ornamental design for a ring as shown.

CHARLES A. BICKFORD.
